READY MADE TIE

Isidor Bronshvaig, Bronx, N. Y.

Application May 23, 1934, Serial No. 727,185

2 Claims. (Cl. 2—150)

This invention relates to a ready made or preformed necktie, and has for an object to provide a necktie which can be easily and quickly put into place and removed and one which will not wrinkle in the ordinary manner. A further object of this invention is to provide a slightly resilient plate, with the aid of which any ordinary four-in-hand necktie may be quickly and easily and semipermanently converted into a ready made necktie. With the metal form of this invention it is possible to take any ordinary four-in-hand necktie and by merely sewing or stitching it according to this invention said necktie may be converted into a ready made or preformed necktie. With this invention it is possible for the store or merchant selling neckties in the usual manner to likewise provide the metal shell used in this invention and thus afford the purchaser of a conventional four-in-hand necktie the option of converting his conventional necktie into a ready made necktie, the merchant or store for a small extra fee taking the necktie of purchaser's selection and having it sewed or stitched to the metal form of this invention, thereby converting the ordinary four-in-hand necktie into a preformed or ready made necktie without the necessity of cutting the original necktie in any manner or of providing any additional piece or pieces for forming a ready made knot.

With the foregoing and other objects in view, as will hereinafter become apparent, this invention comprises the constructions, combinations and arrangements of parts, hereinafter set forth, disclosed and shown on the accompanying drawing. In this drawing,

Figure 1 is a front perspective view of the necktie,

Figure 2 is a front view of the knot portion, showing the outer or front twisted portion of the tie in raised position,

Figure 3 is a sectional view taken on the line 3—3 of Figure 1,

Figure 4 is a side elevation of the metal form, and

Figure 5 is a rear view of the same.

There is shown at 10 the metal shell on which there is to be preformed a knot 11 by properly stitching thereto any conventional four-in-hand necktie 12. This shell 10 and the four-in-hand necktie 12 aside from the thread used in stitching the knot into position form the only two elements necessary in constituting this invention. This shell 10 is shaped as shown in the drawing, being somewhat tubular in depth and

tapering from a curved upper edge 14 to a straight lower edge 15, the side edges 16 and 17 extending toward the rear as shown. The side edge 17 is provided with an upper and a lower stitch receiving aperture 18 and 19 while the side edge 16 is provided with a lower stitch receiving aperture 20.

A tongue 21 struck out from the lower edge 15 adjacent the side edge 16 projects inwardly to resiliently press against the slideable portions 22 of the necktie 12 to hold it in position.

To place the tie 12 in position on the shell 10, the tie is folded at right angles across itself, as shown in Figure 2, so that the rear seam containing section 23 of the tie is visible. A line of stitching 24 serves to hold the tie in this position. This sewed portion is then folded over the top 14 of the shell 10, thus forming a pocket into which the shell 10 may be received. The line of stitching 24 is looped back over the top 14 of the shell 10 and then sewed in position by a stitch through the aperture 18. At the lower portion of the shell 10 the tie is then sewed to gather it somewhat and then secured through the apertures 19 and 20 to the bottom of the shell along the line 25.

Another line of stitching 26 serves to gather the tie so as to snugly fit about the shell 10 and form a neat simulated knot 11. The tie 12 is thus secured to the shell 10 with only three lines of stitching 24, 25 and 26 and the stitching placed through the apertures 18 and 19 and 20.

To place the necktie in position on the neck, the slideable portion 22 is placed around the neck and then brought in between the sides 16 and 17 which are somewhat spaced apart. It is then pulled downwardly thereby slipping the knot 11 into the proper position and the tongue 21 crushing against the slideable portion 22 serves to hold the tie in the proper position on the neck. To remove the tie the slide portion 22 is merely slipped out between the edges 16 and 17 allowing the sides to be removed easily and quickly. As will be apparent, once the tie has been placed in position on the shell 10 there is no wear or tear on the knot simulating portion 11. The knot 11 therefore never gets that frayed or worn out appearance, and the tie 12 may be worn or used as long as desired and still remain neat and clean looking.

If for any reason the necktie 12 is to be discarded the shell 10 may be easily removed therefrom by removing the stitching and applying it to another necktie of conventional construction in the same manner as above described.

The novel features and the operation of this device will be apparent from the foregoing description. While the device has been shown and the structure described in detail, it is obvious that this is not to be considered limited to the exact form disclosed and that changes may be made therein within the scope of what is claimed without departing from the spirit of the invention.

Having thus set forth and disclosed the nature 10 of this invention, what is claimed is:

1. For use in preparing a ready made necktie, a pre-shaped metallic shell having the shape of a necktie knot, said shell tapering from a curved upper edge to a straight lower edge, and being open at its rear from the top to the bottom, a 15 plurality of stitch receiving apertures adjacent

the rear edges of said shell, and a downwardly extending tongue struck inwardly from said shell adjacent its bottom edge to assist in holding slip portions of a tie therein, said tongue ending within the confines of said shell.

2. In a necktie construction, a knot simulating means comprising a pre-shaped metallic shell of tapered tubular construction having an open end, means in said shell for stitching a necktie thereto in knot simulating form, and downwardly extending means struck inwardly from said shell for holding the slip portion of the necktie in proper position, said latter means ending within the confines of said shell.
